(57) **CLAIM**

The ornamental design for a pole anchor, as shown and described.

DESCRIPTION

FIG. 1 is a perspective view of the pole anchor showing our new claimed design;

FIG. 2 is a right-side elevational view of the pole anchor thereof, the left-side elevational view being a mirror image of the right-side elevational view;

FIG. 3 is a front elevational view of the pole anchor thereof; FIG. 4 is a back elevational view of the pole anchor thereof; FIG. 5 is a top plan view of the pole anchor thereof; and, FIG. 6 is a bottom plan view of the pole anchor thereof. The broken lines in the figures show portions of the article that form no part of the claimed design.
